UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

CEMENTING-MACHINE.

1,350,298.

Specification of Letters Patent. Patented Aug. 24, 1920.

Application filed March 4, 1918. Serial No. 220,240.

To all whom it may concern:

Be it known that I, JOHN W. COSGROVE, a citizen of the United States, residing at Medford, in the county of Middlesex and 5 State of Massachusetts, have invented certain Improvements in Cementing-Machines, of which the following description, in connection with the accompanying drawings, is a specification, like reference characters 10 on the drawings indicating like parts in the several figures.

This invention relates to cementing machines and especially concerns those in which the material to be coated is acted upon by a 15 cement-applying member and by a work-engaging member. In accordance with it, a machine is provided by which the cement is applied uniformly to the edges of various articles, particularly those which are sharply 20 bent or curved, and which may readily be arranged to suit different operating requirements.

A feature of my invention consists of a 25 novel work-feeding member, which, while causing an efficient contact of the work with approximately the full width of the applying member does not interfere with the freedom of the work to turn in changing the direction of feed. In the organization illustrated, the feeding member comprises sections 30 which are relatively movable independently of one another so that they may travel at different rates while the member is advancing the work.

35 Another feature concerns novel connecting mechanism for the work support or feeding member which may act from different normal positions. A convenient form of this connection includes coöoperating 40 levers which may be mounted differently with relation to one another to obtain the desired result.

The accompanying drawing illustrates one embodiment of the invention,

45 Figure 1 being a side elevation of the portions of a cementing machine with which this invention is more directly concerned, the connections for the work support being arranged to control it from a normally 50 raised position;

Fig. 2 is a similar view of the reversed connections for the support;

Fig. 3 is a vertical section between adjacent disks of the supporting roll, and

Fig. 4 is a sectional detail of a portion of 55 the applying roll.

Upon the table 10, which, for the purposes of this invention may be considered as a portion of the frame of the machine, is mounted the frame proper designated by the 60 numeral 12. The machine as a whole is of a well-known type, having an elevated tank 14 the flow from which is controlled by a valve 16 delivering the cement to an applying member consisting of a roll 18. This 65 roll is fast upon a horizontal shaft (not shown) journaled in the upper portion of the frame 12 beneath the tank and rotated by a belt engaging fast and loose pulleys 22. The cement is carried from the tank 70 to the work in pockets or depressions 24 in the roll 18, these pockets being in a continuous series about the periphery and being longer in their dimension transversely of the roll. They are separated from one another by relatively thin walls 26. When the 75 pockets are thus wholly divided from one another, the area of cement which each deposits upon the work tends to remain distinct from that deposited by the adjacent 80 pockets, or even to decrease in area and draw together by cohesion. This produces an interrupted and non-uniform coating. To prevent this, I form one or more narrow 85 grooves 28, which are here shown as four in number, circumferentially of the roll connecting all the pockets. These grooves not only lay connecting lines of cement upon the work to break the otherwise uncoated surfaces, but also tend to cause the 90 raised portions of cement deposited by the pockets to draw together or coalesce, so that the work is coated over almost the entire peripheral face of the applying roll. This 95 effect is attained without disturbing the capacity of the pockets for carrying a limited quantity of cement and thus prevent flooding, a condition which would occur were the cement-carrying depression to be in the form of a continuous groove about the roll 100 of the full width of the strip of cement to be applied.

For both supporting and advancing the work, an engaging member is provided be-

low and opposite the applying roll, this preferably consisting of the roll 30 substantially equal in width to the applying roll. It is carried upon a shaft 32 journaled in 5 elevated bearing portions 36, 36 of a lever 34 fulcrumed at 38 upon the frame 12. Rotation is imparted to the roll 30 through spur gearing 40 by which the shaft 32 is joined to the main shaft. The depth of engagement of the teeth of the gearing 40 is such as to permit the lever 34 to swing to a limited extent upon its fulcrum point without interfering with the driving action. The roll 30 is made up of disks furnishing 10 sections which may rotate independently of one another, there being three of these disks here illustrated. The central disk 42 is fast upon the shaft 32, it having a central internally threaded opening to engage a thread 44 upon a reduced portion of the shaft. Inner and outer disks 46 and 48, respectively, at each side of the disk 42 are mounted to turn freely. The disk 46 lies between 42 and annular shoulder 50 on the 15 shaft 32 abutting against the end of the lever 34, while the disk 48 surrounds the outer reduced end of the shaft and is held in place by a bolt and washer 52. To cause the disks 46 and 48 to offer little resistance to turning, anti-friction rolls 54 are interposed between them and the shaft. The effect of this sectional feed roll is that when cement is to be applied to the surface along a straight edge, the positively driven 20 disk 42 advances the work beneath the applying roll, the disks 46 and 48 rotating with it at substantially the same rate through their engagement with the work. Upon angular movement of the work, however, as when shoe soles being cemented along the outer edge of one of their surfaces are turned to follow the curvature, the rate of rotation of the disks 46 and 48 changes, the one at the outside of the curve increasing 25 in angular velocity while that at the inside lags behind the driving disk. These rotary velocities change instantly with the change of direction, so that practically no resistance to the turning of the work is offered. This, in spite of the fact that the roll 30 acts to hold the work up to the full width of the cement-applying surface.

When the applying roll and feed roll are in sufficiently close proximity to press the 30 work between them, it is advanced by their rotation and coated with cement over the area with which the applying roll contacts. If the feed roll is lowered, it carries the work away from the applying roll and the 35 effective feed ceases. The travel of the work, so that the application of cement may begin and end at predetermined points, is controlled by the operator through the raising and lowering of the carrier lever 34, and with it the shaft 32 and feed roll,

about the fulcrum 38. The character of the work or the inclination of the operator may render it easier to have the feed roll normally raised in its feeding relation, to be lowered to introduce the work or stop 40 the advance; or it may be found preferable to have the feed roll normally lowered, from which point it is lifted after the introduction of the work to start the cement-applying action. This invention furnishes 45 mechanism which may be arranged easily and with slight changes in the elements to accomplish either result. The carrier lever 34, as here illustrated, is of the bell-crank type, it having an arm 56 depending from 50 the upper bearing arm. With this arm 56 co-operates a second bell-crank lever 58 fulcrumed upon a bracket 60 secured by wood screws 62, or the like, to the table 10. To the lower horizontal arm of the lever 58 is 55 pivoted a link 64 passing downwardly through a hole in the table for connection to a treadle or other member for actuation by the operator, this not being shown. Through the front portion of the frame 12 60 is threaded a screw 66 secured by a check nut 68 bearing against the frame. The inner end of the screw 66 is so positioned that as the feed roll is raised the arm 56 of the lever 34 contacts with it. It thereby serves 65 to limit and adjust the approach of the feed roll to the applying roll. At the opposite side of the frame, threaded into an opening in a boss 70, is a screw 72 of considerable diameter and having an axial bore. If the 70 feed member is to be normally raised, as is illustrated in Fig. 1, a rod 74 of such diameter that it may move through the opening in the screw 72 is pivoted at its inner extremity by means of an eye 76 and pin 78 to 75 the bifurcated lower end of the arm 56. Surrounding the rod 74, and extending between the lever arm 56 and the inner end of the screw 72, is a helical spring 79, which holds the lever against the stop screw 66 80 and the feed roll raised into co-operation with the applying roll. The resistance of the roll 30 to movement may be varied by turning the screw 72 and thus altering the tension of the spring 79. A spring 80, surrounding the actuating rod 64 between the base of the bracket 60 and the horizontal arm of the lever 58, holds up the rod and connected actuating elements so that the feed roll may not be lowered by their 85 weight.

If the conditions are such that a normally lowered position of the feed roll is preferable, the bracket 60 is secured by its screws in the reverse position illustrated in Fig. 2, 90 another hole being bored through the table to receive the rod 64. When thus located, the upper end of the bell-crank lever 58 rests against the opposite or rear side of the arm 56, from which the rod 74 with its sur- 95

rounding spring has been removed. The spring 80 carrying the weight of the actuating parts is employed as before, but no spring equivalent to 79 is required, since the 5 weight of the lever 84 and elements supported thereby is sufficient to normally maintain the roll at its lowest point. In this direction its movement is limited by contact of the lever 58 with a rod 82, which 10 is fixed in the bore of the screw 72 and which thus serves as an adjustable stop. The screw 66 acts as before to vary the limit of the feeding roll in its upward movement.

15 At the inner coöperating edges of the applying roll and feed roll is shown a gage 84, adjustably fixed upon the top of the outer bearing portion 36 of the arm 34 by means of a screw 86. This gage controls, 20 by its contact with the edge of the work, the width of the strip of cement which is applied. About the periphery of the feed roll at the front, or the side from which the work is introduced, extends a shield 88 25 carried by an arm 90 fixed to the outer bearing portions 36, said shield holding the work from contact with this portion of the feed roll and acting to facilitate its entrance between the feed roll and the applying roll. The general operation of the machine will be obvious without further description.

Having thus described my invention, what I claim as new and desire to secure by Letters Patent is:

1. A machine for operating on curved objects having, in combination, a member for performing the operation and a work-supporting and feeding mechanism comprising 40 a driven shaft, a rotated disk secured to the shaft and having a work-feeding face on its periphery, and work-supporting disks arranged on either side of the feed disk and free on the shaft, the outer and inner work-supporting disks being adapted to turn respectively forwardly and backwardly relatively to the intermediate work-feeding disk as the work is swung in feeding curved portions thereof past the operating point.

50 2. A machine for operating on curved objects having, in combination, a member for performing the operation and a work-supporting and feeding mechanism comprising a driven shaft, a rotated disk secured to the shaft and having a work-feeding face on its periphery in vertical alinement with the working member, and a work-supporting disk on the shaft at one side of the feeding disk and free on the shaft to permit it 55 to be turned by rolling contact with the work either forwardly or backwardly relatively to the feeding disk as the work is swung while being fed to present curved portions thereof to the working member.

60 3. A machine for operating on soles hav-

ing, in combination, a cement-applying member 18, a feed shaft 32, a narrow feed disk 42 having a driving connection with the shaft and located under the working point of the member 18 on the sole, and 70 disks 46 and 48 free on the shaft and supporting the work at either side of the feed disk, said parts being organized to permit the sole to be swung easily on the narrow feed disk while the disks 46 and 48 afford 75 supplemental support and offer no resistance to the swinging movement of the sole.

4. In a machine of the class described, opposite rotatable operating and feeding members, the feeding member consisting of 80 a plurality of sections relatively movable independently of one another and contacting with the work over a width approximately that of the operating member.

5. In a machine of the class described, 85 opposite rotatable operating and feeding members, the feeding member consisting of a plurality of relatively movable sections contacting with the work over a width approximately that of the operating member. 90

6. In a machine of the class described, opposite rotatable operating and feeding members, the feeding member consisting of a plurality of independently movable sections contacting with the work over a width approximately that of the operating member, and means for positively rotating a section 95 of the feeding member.

7. In a machine of the class described, oppositely rotatable operating and feeding 100 members, the feeding member consisting of a central section and outer sections movable independently of the central section, said sections together contacting with the work over a width approximately that of the operating member, and means for positively rotating the central section. 105

8. In a machine of the class described, a rotatable operating roll, an opposite feed roll consisting of a plurality of independently rotatable sections, and means for driving the section opposite the central portion of the operating roll. 110

9. In a cementing machine, a cement-applying roll, and a feed roll situated below the 115 applying roll and including a plurality of independently rotatable sections.

10. In a cementing machine, a cement-applying roll, a power-driven shaft, a feed disk fast upon the shaft and coöperating with the 120 applying roll, and other disks cooperating with the applying roll and being mounted to rotate freely upon the shaft.

11. In a cementing machine, a cement-applying roll, a power-driven shaft, a feed disk 125 fast upon the shaft and coöperating with the applying roll near the center of its applying face, and a work-supporting disk rotatable upon the shaft at each side of the feed disk.

12. In a cementing machine, a cement-ap-

plying roll, a power-driven shaft, a feed disk fast upon the shaft and coöperating with the applying roll near the center of its applying face, a work-supporting disk rotatable upon the shaft at each side of the feed disk, and anti-friction bearings interposed between the shaft and said supporting disks.

13. In a machine of the class described, a work-engaging member, and connections for 10 moving the work-engaging member, said connections including an element constructed and arranged to permit it to be reversed with respect to an associated connecting element and thereby to move the work-engaging member from different normal positions.

14. In a machine of the class described, a work-engaging member, connections for moving the work-engaging member, said connections including an element constructed 20 and arranged to permit it to be reversed with respect to an associated connecting element and to thereby move the work-engaging member from different normal positions, a member adjustably mounted in proximity to 25 the connections, and a member contacting with the adjustable member and the connections to control the movement of the work-engaging member.

15. In a machine of the class described, a work-engaging member, connections for 30 moving the work-engaging member, said connections including an element constructed and arranged to permit it to be reversed with respect to an associated connecting element 35 and to thereby move the work-engaging member from different normal positions, a member adjustably mounted in proximity to the connections, and a member contacting with the adjustable member and the connections to control the movement of the work-engaging member, the adjustable member 40 being arranged to coöperate with different movement-controlling members in the reverse positions of the connections.

16. In a machine of the class described, a work-engaging member, and connections for moving the work-engaging member, said connections including contacting levers, one of which levers may be mounted in either of 50 two positions to engage the associated lever at opposite sides and thereby cause the connections to differently control the work-engaging member.

17. In a machine of the class described, a work-engaging member, connections for 55 moving the work-engaging member, said connections including contacting levers, one

of which levers may be mounted in either of two positions to engage the associated lever at opposite sides and thereby cause the connections to differently control the work-engaging member, and an adjustable member having an opening for the reception of a member coöperating with either of the two levers. 60

18. In a cementing machine, the combination with a frame, of a cementing roll rotatable thereon, a work-supporting member coöperating with the cementing roll, a carrier lever for the work-supporting member 70 fulcrumed upon the frame, a bracket, an actuating lever fulcrumed upon the bracket for coöperation with the carrier lever while being free to move independently thereof, and a link for movement by the operator connected to the actuating lever. 75

19. In a cementing machine, the combination with a frame, of a cementing roll rotatable thereon, a work-supporting member coöperating with the cementing roll, a carrier lever for the work-supporting member 80 fulcrumed upon the frame, a bracket, and an actuating lever fulcrumed upon the bracket for coöperation with the carrier lever while being free to move independently thereof, 85 the bracket being arranged to be secured to the frame in two positions to bring the actuating lever into contact with opposite sides of the carrier lever.

20. In a cementing machine, the combination with a frame, of a cementing roll rotatable thereon, a work-supporting member coöperating with the cementing roll, a carrier lever for the work-supporting member 90 fulcrumed upon the frame, a bracket, an actuating lever fulcrumed upon the bracket for coöperation with the carrier lever, a screw threaded into the frame, and a rod coöperating with the screw and with one of the levers. 95

21. In a cementing machine, the combination with a frame, of a cementing roll rotatable thereon, a work-supporting member coöperating with the cementing roll, a carrier lever for the work-supporting member 100 fulcrumed upon the frame, a bracket, an actuating lever fulcrumed upon the bracket for coöperation with the carrier lever, a screw threaded into the frame and being provided with an opening, and a rod situated in the opening and contacting with one of the 105 levers. 110

In testimony whereof I have signed my name to this specification.

JOHN W. COSGROVE.
